HOOK SETTING MACHINE.
APPLICATION FILED JULY 2, 1904.

2 SHEETS—SHEET 2.

UNITED STATES PATENT OFFICE.

ANDREW RAICHE, OF QUINCY, MASSACHUSETTS, ASSIGNOR, BY MESNE ASSIGNMENTS, TO THE PEERLESS MACHINERY COMPANY, A CORPORATION OF MASSACHUSETTS.

HOOK-SETTING MACHINE.

No. 843,697.

Specification of Letters Patent.

Patented Feb. 12, 1907.

Application filed July 2, 1904. Serial No. 215,093.

To all whom it may concern:

Be it known that I, ANDREW RAICHE, a citizen of the United States, residing at Quincy, county of Norfolk, and State of Massachusetts, have invented an Improvement in Hook-Setting Machine, of which the following description, in connection with the accompanying drawings, is a specification, like letters on the drawings representing like parts.

Prior to this invention in machines of this class it has been customary to supply a spindle with a hook while the spindle occupied its lowered position in line with an anvil, and thereafter the spindle has been raised to thrust the tubular shank of the hook through a hole previously punched in the stock, or the shank of the hook has been thrust through the stock, and in both these machines it has been customary to feed the stock by hand.

In the form of machine wherein the holes for the shanks of the hooks are punched on a separate machine the stock is fed by hand, so that one after the other of the punched holes is passed over the shanks of the hooks. The other class of machine, where the shanks of the hooks have been forced through the stock, is employed only in connection with cheap work, where faults in the spacing of the hooks, due to inequality of feeding the stock by hand, are considered immaterial.

Herein I have, as I believe, for the first time constructed a device for securely holding a hook while its shank is passed through the stock, said device, while said shank is in the stock, being automatically moved laterally to effect the feeding of the stock.

In my improved machine it is possible to automatically insert and accurately space the hooks in the stock, and by automatically feeding the stock after setting each hook it becomes possible to set the outside of the neck of each hook parallel with the edge of the parts or flies of the shoe in which the hooks are set.

Figure 1, in side elevation, represents a hook-setting machine embodying my present invention, the parts being in their inoperative positions or positions of rest. Fig. 2 is a detail showing a portion of the hook-sustaining plate at the upper end of the plunger employed for thrusting the shanks of the hooks

through the stock, a part of the raceway, and a device for feeding the hooks one at a time into the hook-sustaining plate. Fig. 3 is a detail showing the hook-sustaining plate in its hook-receiving position. Fig. 4 is the front or left-hand elevation of the machine shown in Fig. 1. Fig. 5 is a detail of the plunger and hook-sustaining plate detached from the machine. Fig. 6 is a detail showing part of the means employed for feeding the spindle and hook-sustaining plate laterally when feeding the stock, and Fig. 7 shows part of the table-plate and an edge-gage.

The framework of the machine is of suitable shape to sustain the working parts. One part of this framework sustains a work-table A', provided with a suitable edge-gage A², which may be adjusted with relation to the front of the work-table and the point where the shanks a of the lacing-hooks a' are thrust into the stock.

The upper part of the framework has suitable bearings B to sustain a rock-shaft B', having at its rear end a crank B², provided with a crank-pin that is engaged by the upper end of a link B³, the lower end B⁴ of which is slotted to embrace the main driving-shaft B⁵, said lower end having projecting from one side thereof a suitable stud B⁶, that enters the groove of a face-cam B⁶, fast on said shaft. The shaft B' has at its front end a disk C, provided with a crank-pin C', that carries a slide-block C², said slide-block entering a groove in a block C³, secured to the shank C⁴ of the anvil D by means of a suitable set-screw C⁵, and as said shaft is rocked the anvil is lowered and raised as required. The dotted circles, Fig. 4, above and below the crank-pin C' show the positions occupied by the crank-pin as the shaft B' is rocked. The shank C⁴ is free to slide in suitable bearings C⁶, forming part of the framework, and said shank at its upper end has a hand-wheel C⁷, that may be turned to provide for the vertical adjustment of said shank and the anvil D at the end thereof, the said shank being threaded, as at C⁸, to engage threads of the block C³, said threads coacting with the set-screw C⁵, affording absolute accuracy of adjustment and maintaining the adjustment to exactly the proper point with relation to the thickness of the stock.

The anvil D is constructed of steel and is se-

cured to the lower end of the shank C⁴ in any usual manner, and in its lowest position during the setting of the shank of the hook in the stock the anvil is made to act upon the upper side of the stock supported on the work-table.

Fig. 1 shows the stock, supposed to be leather D', as resting on the work-table, and the stock is acted upon at its upper side by a presser-foot D², shown as angular in shape and connected by a suitable clamping-screw D³ with a block D⁴, secured to a slide-rod D⁵ by a suitable screw, said block and presser-foot being adjustable vertically to correspond with the thickness of the stock in which the hooks are being set. The presser-foot must be raised automatically from the stock after setting each hook, and to do this I have in the present instance shown presser-foot-lifting means comprising a link b, jointed to one end of the block D⁴, said link being in turn jointed with the end of a lever b', mounted on a fulcrum b², carried by the framework.

The lever b' has connected with it at b³ a link b⁴, that is jointed to the upper end of a rod b⁵, movable vertically in suitable bearings b⁶, said rod having at its lower end a roller b', that is acted upon by the periphery of a cam b⁸ to raise said rod and the lever when the presser-foot is to be lifted automatically when the stock is to be released that it may be fed.

The rod b⁵ has an attached collar b⁹, that sustains the lower end of a spring b¹⁰, said spring acting normally to keep the presser-foot yieldingly upon the face of the stock. This presser-foot has to be raised prior to inserting the stock and before starting the machine in operation, and to do this I employ a lever b¹², preferably forked at one end to embrace the rod and act upon the collar b⁹, said lever having its fulcrum at b¹³ and having a backward extension with which is connected a link b¹⁴, in turn attached to some suitable foot-treadle.

The main shaft b⁵ is provided with a set of cams E, F, G, and H. The cam E, represented as a face-cam, acts on a roller or other stud e at the lower end of a lever e', having its fulcrum at e², said lever being slotted at its upper end to receive a pin e³, extending from the hook-supplying device, represented as a sliding bar e', a lapel to be reciprocated in a suitable guideway e⁵, sustained by the framework behind a cover-plate e⁶. The front end of the hook-sustaining device is adapted when thrust to the left or forwardly in Figs. 1 and 2 to meet the outside of the neck of the hook and move the same off from a shelf or projection e⁷, which is stationary with relation to the end of the usual raceway e⁸, the heads of the hooks as they leave the raceway being sustained by said projection e⁷ in the path of movement of the hook-supplying device e⁴ as the latter is actuated by the lever e'.

The cam G rotates inside and contacts with the parallel faces of a yoke G', shown as

guided by uprights G², erected on the base of the framework, and raises and lowers said yoke for purposes to be hereinafter described.

The yoke G' has a plane face 2, represented as occupying a position in a horizontal plane, and said face sustains the lower end of a spindle 4, the latter being hollow for most of its length and being threaded at its upper end to receive a threaded boss 5 of the head 6 of the spindle. The head 6 at its upper side has a recess g⁶ to receive from the raceway the hook to be set, and said head is grooved (see Fig. 2) to constitute a guideway for the reception and guidance of the shank g⁴ of the hook-sustaining plate g⁷, the shape of which is best shown in Figs. 2 and 3.

The sustaining-plate has a shoulder 8, against which strikes the inner side of the neck of the hook, and in line with said shoulder there is a notch 10, that when the plate is moved forwardly from the position, Fig. 3, into its operative position, Fig. 2, embraces the neck of the hook.

The setting-plate derives its motion from an elbow-lever g³, pivoted at 12 and having a stud g², that enters a slot (see Fig. 5) in the upper end of a rod g', having a stud 13, said rod entering the hollow spindle, the stud 13 extending outwardly through a slot 14 in the spindle 4, where it receives a roller g.

The rod g' in Fig. 5 is represented as surrounded by a spiral spring h, the lower end of which rests on a shoulder h' of said rod, and said spring acts normally to depress the rod and maintain the hook-sustaining plate in its operative position with the roller g on the actuator f', so that when said actuator constituting part of a parallel motion is raised, as will be described, the sustaining-plate will be withdrawn from the throat of the hook.

Each hook is taken by the hook-presenting device from the raceway shown in Fig. 2 and is transferred from the raceway to the hook-sustaining plate when the latter is in the position shown in Fig. 3, the throat of the hook-sustaining-plate being stopped by contact with the shoulder 8 of said plate occupying, as represented in said figure, its hook-receiving position in or with relation to the spindle, and thereafter the hook-sustaining plate g⁷ is moved forwardly in the throat of the hook until (see Fig. 2) the notch 10 of said plate embraces the neck of the hook, as represented in Fig. 2, said plate thereafter holding the hook firmly seated during the operation of expanding the shank of the hook in the stock and while the stock is being fed after the shank of the hook has been upset in the stock, the plate during the feeding operation of the stock occupying a position in the throat of the hook.

The yoke G' has a stud f, upon which is mounted an elbow-lever f', the lower arm of which is provided with a roller f², that is normally maintained in contact with the pe-

iphery of the irregular cam H through the spring h. The upper end of the longer end of the lever f' is jointed at f³ to an actuator f⁴ in turn jointed at f⁵ on the upper end of a link f⁶, the lower end of which is free to turn about a stud f⁷, carried by the yoke G'.

It will be understood in the revolution of the cam-shaft that the cam H, acting through the roller f², will turn the elbow-lever f' and raise and lower the actuator f⁴, the upper side of the latter being maintained in the same horizontal plane, notwithstanding it is raised and lowered, this being effected through the link f⁶. The upper side of the actuator 15 sustains the roller g.

The cam H is so shaped with relation to cam G that for part of the movement of the yoke G' the actuator f⁴ is moved in unison with the yoke, as when the yoke is rising and 20 while the spindle is being moved, as will be described, laterally along the actuator for feeding the stock; but at the end of said stock-feeding stroke and just before the slide begins to descend the actuator is raised by a 25 part of the cam H to effect the withdrawal of the hook-sustaining plate from the throat of the hook, the latter having been set in the stock then sustained on the table-plate.

The cam F or feed-actuator rotates be- 30 tween the forked ends of a lever F' or device interposed between said feed-actuator and the block F³, said lever being pivoted on a stud F², sustained in the back of said block F³, adapted to be slid horizontally with its 35 spindle, which is guided therein as the spindle is moved vertically, said block having at its rear side a hole to receive a guide-rod F⁴, that is free to slide through suitable ears F⁵ of the framework.

40 The lever F' is slotted at m' to receive a fulcrum m², that is made adjustable vertically in the framework of the machine by movement of the forked end m³ of a feed-controller m⁴, having its fulcrum at m⁵. Said feed-con- 45 troller has a pointer m⁶, (see Fig. 4,) that co- operates with a series of lines of an index m⁷, formed on an upright m⁸, suitably secured to the framework. The index-lines m⁷ indicate the positions that the feed-controller must 50 occupy in order to secure a certain definite spacing of the hooks for different-sized shoes.

In operation let it be assumed, reviewing 55 Figs. 1 and 4, that the spindle has been lowered and that when in its extreme lowered position the hook-sustaining plate was slightly retracted by slightly lifting the actuator and that the hook-presenting device has 60 acted and has transferred a hook from the raceway into the recess g⁶ of the head of the spindle, as represented in Fig. 3, and that the actuator has been then started and moved sufficiently to enable the spring h to move the hook-sustaining plate to enter the throat 65 of the hook. In this condition, Fig. 1, the

spindle starts on its rising movement. After the hook-setting plate has been moved forwardly to engage the throat of and lock the hook in fixed position with relation to the spindle the spindle in the continued motion 70 of the machine is raised from the position shown in full lines, Fig. 4, into the dotted-line position, and the shank of the hook is passed through the stock on the work-table, held thereon by the action of the presser foot on the upper side of the stock. Prior to the shank of the hook being passed through the stock the anvil is caused to descend upon the surface of the stock and remains in its lowered position while the shank of the hook 80 is penetrating the stock, the hollow shank of the hook contacting with the surface of the anvil being turned outwardly and flanged, thus setting the shank of the hook firmly in the stock. This done, the anvil immediately 85 retires from the stock, the presser-foot is raised, and the cam F moves the block F³ horizontally to the left, Fig. 4, taking with it the devices carried thereby and holding the hook, among which is the hook-sustaining plate, 90 yet in engagement with the hook, the shank of which has been set in the stock and the stock is fed for just the proper distance, that depending upon the size of the shoe in which the hooks are being set, as indicated by the 95 position of the feed-controller m⁴.

The block F³ having been moved to feed the stock for exactly the proper distance, the presser-foot descends upon the stock on the feed-table and immediately thereafter the 100 actuator is raised sufficiently by the cam H with relation to the upper end of the yoke G' to raise the rod g' and withdraw the hook-sustaining plate from the throat of the hook preparatory to the descent of the setting-spindle which is effected through the action 105 of cam G. The yoke G' is made to descend by the cam H after the withdrawal of the hook-sustaining plate from the throat of the hook and after the stock has been fed. As 110 the yoke arrives in its lowest position, with the hook-sustaining plate in position to be again supplied with a hook from the raceway, the spring h acts to move the hook-sustaining plate forwardly into the throat of the 115 hook.

As soon as the work has been fed into position with relation to the spindle the hook-sustaining plate is moved forward quickly, as stated, to engage, lock, and retain the hook 120 in setting position while the operations just described are repeated.

Having fully described my invention, what I claim as new, and desire to secure by Letters Patent, is—

1. In a hook-setting machine, an anvil, a work-table, a spindle, a hook-sustaining plate slidably mounted therein and adapted to receive upon it and hold the hook while the latter is being thrust through the stock 130

- and the anvil is expanding the shank of the hook to set the same in the stock, means to move laterally the spindle and hook-sustaining plate while the plate is in engagement with the hook to thereby feed the stock over the work-table, and means to slide said hook-sustainer in said spindle at an angle to the longitudinal axis thereof to withdraw said plate from the throat of a set hook.
2. In a hook-setting machine, an anvil, a work-table having a slot open at its work-delivering end from which end the stock is fed after a hook has been set therein, a device to enter the throat of, clamp, and hold a hook while the same is being set in the stock, means to move said device while yet in engagement with the said hook after a hook has been set to effect the feeding of the stock over said work-table.
3. In a hook-setting machine, a horizontally-slidable block, a spindle carried thereby and provided with a hook-sustaining plate, a rod connected with said hook-sustaining plate and within said spindle, a work-table to sustain the stock above said spindle, means to move said spindle vertically in said sliding block that said plate may enter the throat of, hold, and clamp a hook to be set, means to raise said spindle and its hook-setting plate in engagement with the hook to force the shank of the hook through the stock on the upper side of said work-table, means to move horizontally said slidable block while the hook-setting plate yet engages the hook, the shank of the latter having been upset in the stock, and a device to retain said hook-sustaining plate in engagement with said hook while said block is being moved horizontally to effect the feeding of the stock over said work-table.
4. In a hook-setting machine, a slidable block, a spindle carried thereby and provided with a hook-sustaining plate for holding and clamping on the spindle a hook to be set, a work-table to sustain the stock, means to move said spindle to set the hook in the stock, a lever, means to actuate said lever to move said block, a fulcrum for said lever, and means for adjusting said fulcrum to vary the extent of movement of said block through said lever.
5. In a hook-setting machine, a slidable block, a spindle carried thereby and provided with a work-sustaining plate for holding and clamping on the spindle a hook to be set, a work-table to sustain the stock, means to move said spindle to set the hook in the stock, a lever, means to actuate said lever to move said block, a fulcrum for said lever, means for adjusting said fulcrum to vary the extent of movement of said block through said lever, and means for moving said work-sustaining plate to release said hook.
6. In a hook-setting machine, a work-table to sustain the stock, an anvil, means to place the same in contact with the stock on the work-table, a block, a spindle held loosely in said block, a hook-sustaining plate carried by said spindle, means for causing said plate to enter the throat of the hook, means for moving said spindle toward the work-table and anvil, an actuator sustained by the means for moving said spindle toward said table, and means for moving said actuator to withdraw the hook-sustaining plate from the hook.
7. In a hook-setting machine, a work-table to sustain the stock, an anvil, a block, a spindle held loosely in said block, a hook-sustaining plate carried by said spindle, means for moving said spindle toward the work-table and anvil, an actuator sustained by the means for moving said spindle toward said table, and means intermediate said hook-sustaining plate and said actuator for sliding the hook-sustaining plate at right angles to the longitudinal axis of said spindle, and means to slide said block at right angles to the longitudinal axis of the anvil.
8. In a hook-setting machine, a spindle, a hook-sustaining plate guided thereby and having a shoulder, and a notch; combined with means to supply a hook to said plate, that the throat of the hook may embrace said shoulder, and means to thereafter move said plate that its notch may embrace the neck of the hook sustained by said shoulder and clamp the same to the spindle.
9. In a hook-setting machine, a spindle, a hook-sustaining plate guided thereby having a shoulder against which the inner side of the neck of the hook contacts, and a notch; combined with means to supply a hook to the said plate, means to move the hook-sustaining plate longitudinally that the notch may embrace the neck of the hook and clamp the same to the spindle, means to hold said hook-sustaining plate in position to retain the hook fixedly in the spindle while setting the shank of the hook in the stock and means for moving said plate to feed the stock after setting each hook substantially as described.
10. In a hook-setting machine, a work-table, an anvil, means to place the anvil against the upper side of the stock, a spindle having a device to enter the throat of a hook and clamp the same in said spindle, means to impart to said spindle upward movement in the operation of setting a hook in the stock, and means for moving said spindle horizontally for feeding the stock.
11. In a hook-setting machine, a work-table, an anvil, means to place the anvil against the upper side of the stock, a spindle, means to feed a hook to said spindle, means to impart to said spindle four motions, an upward movement when setting the shank of a hook in the stock, a lateral movement during the feeding of the stock, and then a downward and backward movement, a hook-sustaining plate carried by said spindle, means to recip-

5 rocate said plate to enter the throat of a hook prior to setting the same in the stock, and means for withdrawing said plate after setting the hook and prior to the descent of the spindle.

12. In a hook-setting machine, a hollow spindle having at its upper end a recess for the reception of the head of a hook, a hook-sustaining plate mounted loosely at the upper end of said spindle, a lever engaging said hook-sustaining plate, a rod connected with said lever, a spring coacting with said rod and contained in said hollow spindle to cause said hook-sustaining plate to enter the throat of a hook, and means to effect the withdrawal of said hook-sustaining plate from the throat of said hook as and for the purpose described.

13. In a hook-setting machine, a hollow spindle having at its upper end a recess for the reception of the head of a hook, means to raise and lower said hollow spindle a hook-sustaining plate mounted loosely in the upper end of said spindle, a lever, a rod connected with said lever, and means for automatically moving said rod vertically to move said lever in a direction to withdraw the hook-setting plate from the throat of the hook.

14. In a hook-setting machine, a table-plate, an anvil, a block located below said table-plate, a guide-rod, devices located in said block to engage and hold a hook, means to move said hook-holding means vertically in

said block to pass the shank of a hook upwardly through the stock and upset said shank against said anvil, an adjustable feed-controller, and means to move said block and the hook-holding devices automatically in a horizontal plane below said table-plate while said devices engage the hook, the shank of which has been set in the stock to effect accuracy in movement of the stock to space the hooks with relation one to the other, according to the size of the shoe.

15. In a hook-setting machine, a yoke, means to move the same, means to guide said yoke, a spindle sustained by said yoke, a block having an attached slide-rod, guides for said rod, a spindle mounted loosely in said block, devices carried by said spindle to engage and clamp a hook and hold the same while being set in the stock, and to then release the hook, means to move said yoke vertically, and independent means for moving said block and spindle in a line transverse the longitudinal axis of said spindle for a greater or less distance according to the spacing desired between one and the next set-hook.

In testimony whereof I have signed my name to this specification in the presence of two subscribing witnesses.

ANDREW RAICHE.
